UNITED STATES PATENT OFFICE

MURDOCK MACDONALD, OF CLEVELAND, OHIO

TICKET HOLDER

Application filed February 10, 1927. Serial No. 167,147.

The present invention relating as indicated to ticket holders, is particularly directed to my improved device for releasably and slidably holding a pad of what are commonly called transfers for use on street railways, bus lines and the like. One of the principal objects of the invention is the provision of such a device which will be simple in construction and convenient in operation to permit the marking and tearing off of sections of a pad of tickets or transfers from the stubs to indicate both the date and hour of issuance. To the accomplishment of the foregoing and related ends, said invention, then, 15 consists of the means hereinafter fully described and particularly pointed out in the

claims.

a loop at the central portion which presses the forward plate 8 against the upper surface of the pad; the ends of this spring being extended rearwardly from the shaft 7 and held in inwardly stamped lugs 14 formed from the sides 2 and 3 of the plate 1. By depressing the rearward portion 11, the plate 8 is lifted slightly away from the surface of the pad, thus relieving the pressure thereon and allowing the pad to be slipped longitudinally of the holder to bring any desired portion or marking beneath the tearing-off edge 10.

The plate 9 is provided with up-turned ears 15 at its ends between which is mounted a shaft 16 and on this shaft is slidably mounted a collar 17 carrying a tearing-off pointer 18 which projects forwardly over the edge 10 and is in substantially the same horizontal plane as the plane of the edge 10 so that it lies in contact with the uppermost ticket on the pad. The pointer 18 may be constructed in any suitable way to be provided with a slight pressure holding it in any position in which it is placed along the shaft 16 and in position against the uppermost ticket.

Referring now to Fig. 4, there is shown the transfer itself which is provided in its forward half and along the left margin with the names of the months of the year and along its other margin with the names of the car lines or routes on which the transfer is to be used.

When the transfers are issued to the conductors, the month of the year and the line on which they are to be used is indicated by appropriate punches in the two marginal portions. The other half of the transfer carries along either margin, in this case the left margin, numbers running from 1 to 12 and indicating the hours of the day or night while transversely of the ticket are

printed at spaced intervals, the numbers 15, 30 and 45 indicating the quarter hours. These numbers may either be repeated at various intervals along this portion of the ticket or the ticket may be lined longitudinally into quarters or otherwise marked so that a suitable forming of the torn-off edge of the ticket opposite one of such columns of numbers will indicate the quarter hour while

20 The annexed drawing and the following description set forth in detail certain mechanism embodying the invention, such disclosed means constituting, however, but one of various mechanical forms in which the principle of the invention may be used.

In said annexed drawing:—

25 Fig. 1 is a plan view of my improved holder; Fig. 2 is a side elevation of the same; Fig. 3 is a section on the line 3—3 in Fig. 1; and Fig. 4 is a plan view of a transfer after the severance from the stub by means of my improved holder.

Referring now to Fig. 1, the holder is shown as consisting of a metal plate 1 provided with two parallel upturned sides 2 and 3. The plate thus forms an open shallow box in which a pad 4 of tickets or transfers may be held, the tickets projecting beyond the forward edge 5 of the plate and being slidable longitudinally of the shallow box. Intermediate the ends of the holder or box 35 1, the sides 2 and 3 thereof are formed with upstanding ears 6 in which a shaft 7 is mounted.

Pivottally mounted upon the shaft 7 is a plate 8 provided with a forwardly extending element 9 having a tearing-off edge 10 and a rearwardly extending portion at an elevation spaced from the upper surface of the pad 4 and provided with a recess 12 for the hand or finger of the operator. A coil spring 50 13 is mounted on the shaft 7 and formed into

the point at which the ticket is torn off will indicate the hour. The pad of tickets may be moved longitudinally of the holder to bring the appropriate hour beneath the tearing-off edge 10 of the holder and the notched pointer 18 may then be progressively slipped across the shaft 16 so that the notch formed in the torn edge of the transfer will lie opposite to the appropriate designation of the 10 quarter hour and thus both the hour and the quarter hour will be marked automatically on the torn-off ticket without any further attention by the conductor after the pad has first been adjusted longitudinally in the holder and the pointer 18 has been adjusted transversely of the holder in the manner indicated.

The present holder provides a simple and extremely economical device for receiving and holding a pad of transfers and also provides means for conveniently marking transfers for the hours for which they are good which is done automatically as the transfers are torn from the stubs.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a device of the class described, the combination of a plate adapted to receive a pad of tickets, a projection extending upwardly from each side of said plate intermediate its ends, a pin carried by said projections, a lever, a pair of ears projecting upwardly from said lever intermediate its ends, said ears being mounted on said pin, one end of said lever having a width at least as great as that of said pad, and means urging said lever end into engagement with said pad.

2. In a device of the class described, the combination of a plate adapted to receive a pad of tickets, a projection extending upwardly from each side of said plate intermediate its ends, a pin carried by said projections, a lever, a pair of ears projecting upwardly from said lever intermediate its ends, said ears being mounted on said pin, one end of said lever having a width at least as great as that of said pad, and being provided with a tearing edge, and means urging said edge into engagement with said pad.

3. In a device of the class described, the combination of a plate adapted to receive a pad of tickets, a projection extending upwardly from each side of said plate intermediate its ends, a pin carried by said projections, a lever, a pair of ears projecting upwardly from said lever intermediate its ends, said ears being mounted on said pin, one end of said lever having a width at least

as great as that of said pad and being provided with a tearing edge, and a coiled spring sleeved on said pin, one portion of said spring bearing on said lever arm and urging said tearing edge into engagement with said pad.

4. In a device of the class described, the combination of a plate adapted to receive a pad of tickets, a pin carried by said plate and extending transversely thereof above the surface of said plate, a lever, a pair of ears projecting upwardly from said lever intermediate its ends, said ears being mounted on said pin, one end of said lever having a width at least as great as that of said pad and being provided with a tearing edge, a pair of ears projecting upwardly from said lever adjacent said edge, a rod carried by said ears, means slidably carried by said rod and projecting beyond said edge, and means urging said edge into engagement with said pad.

5. In a device of the class described, the combination of a plate adapted to receive a pad of tickets, a pin carried by said plate and extending transversely thereof above the surface of said plate, a lever, a pair of ears projecting upwardly from said lever intermediate its ends, said ears being mounted on said pin, one end of said lever having a width at least as great as that of said pad and being provided with a tearing edge, means carried by said lever adjacent said edge, said means being movable transversely of said lever and projecting beyond said edge, and means urging said edge into engagement with said pad.

6. In a device of the class described, the combination of a plate adapted to receive a pad of tickets, a pin carried by said plate and extending transversely thereof above the surface of said plate, a lever, a pair of ears projecting upwardly from said lever intermediate its ends, said ears being mounted on said pin, one end of said lever having a width at least as great as that of said pad and being provided with a tearing edge, a pair of ears projecting upwardly from said lever intermediate its ends, said ears being mounted on said pin, one end of said lever having a width at least as great as that of said pad and being provided with a tearing edge, a pair of ears projecting upwardly from said lever adjacent said edge, a rod carried by said ears, means slidably carried by said rod and projecting beyond said edge, and a coiled spring carried by said rod, a portion of said spring bearing on said lever to urge said edge into engagement with said pad.

Signed by me, this 31st day of January, 1927.

MURDOCK MACDONALD.
